APPARATUS FOR HANDLING STRIP MATERIAL

Myles Morgan, Worcester, Mass., assignor to Morgan Construction Company, Worcester, Mass., a corporation of Massachusetts

Application July 24, 1939, Serial No. 286,118

14 Claims. (Cl. 271—2.2)

This invention relates to apparatus for handling strip metal, and more particularly to the handling of comparatively wide strip metal as it is delivered from a rolling mill.

In the hot rolling of thin narrow metal strip in the past, it has been a common practice to turn the stock on edge after it leaves the last stand of the rolling mill and then pass it through pinch rolls and a delivery guide to an apron conveyor which moves in the same direction as the stock but at a much lower speed. By oscillating the delivery guide in a horizontal plane, the stock issuing therefrom is caused to fold back and forth in a series of loops which are carried along on the conveyor. The conveyor transports the stock to suitable reels which form it into cylindrical coils. Because of the back and forth folding of the stock and the slow speed at which the stock approaches the reels, the operator has ample time to attach the front end of each piece of stock to a reel, form the coil, and remove the completed coil from the reel before the next piece arrives at the reel. Furthermore, the stock has an appreciable time to cool during its travel with the conveyor. The advantages of such an arrangement of apparatus are not limited to narrow strip but are just as applicable to wide strip. However, the front portion of the strip tends to tip laterally after leaving the oscillating guide and it is a very difficult task to turn wide strip on edge again and enter its front end in the reel. For this reason heretofore only relatively narrow strips have been subjected to the process described.

It is accordingly the main object of the invention to so improve the prior apparatus above-described as to render it capable of handling comparatively wide metal strips successfully.

It is a further object of the invention to provide a comparatively simple, inexpensive and dependable apparatus adapted for use with metal strips of considerable width, and including a conveyor and means associated therewith, to fold the stock back and forth in a horizontal plane, the stock remaining in an upright position with one edge resting on the conveyor.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is a plan view of an apparatus for handling strip metal;

Fig. 2 is a side elevation of the apparatus;

Fig. 3 is a section on the line 3—3 of Fig. 1; and

Fig. 4 is a diagram of certain electrical circuits. The embodiment illustrated comprises a pair of vertical pinch rolls 10 mounted in a housing 11 and arranged to be rotated by any suitable source of power. At the discharge side of the pinch rolls is a delivery guide or so-called "vibrator" 12 having a pair of idler rollers 14 therein. This vibrator 12 is oscillated in a horizontal plane in a well-known manner. Immediately beyond the vibrator is a flat horizontal table 15, and immediately beyond the table is an apron conveyor 16 comprising a series of flat horizontal plates 18 secured to endless chains 19 which extend around rotatable sprocket wheels 20. Upright side guards 21 are mounted on opposite sides of the table 15 and conveyor 16. The apparatus as so far described is of old and well-known construction, and in the operation thereof hot metal strip from a rolling mill passes between the pinch rolls 10, through the vibrator 12, and across the table 15, to the conveyor 16. The oscillation of the vibrator causes the stock to fold back and forth in long loops on the conveyor.

This mode of operation will proceed satisfactorily with comparatively narrow stock, but if wide stock is supplied to the apparatus, certain difficulties arise. When the front end of the strip issues from the vibrator, this front end may tip over laterally before there has been any time available to form the desired loops, and if this does occur it is very difficult to turn the stock on edge again, as is necessary to enter the stock in the reel. The wider the stock may be in relation to its thickness, the more serious this problem becomes. In order to overcome this difficulty, I provide means to support the front portion of the stock laterally for a brief period until a few loops have been formed, whereupon the supporting means is moved out of the path

of the stock to allow the stock to be carried along by the conveyor. In its preferred form this supporting means comprises a pair of upright gates 23 mounted above the conveyor 16. When these gates are closed, as shown in Fig. 1, they form a V-shaped barrier which converges in the direction of stock travel. Each gate 23 is secured near its outer edge to a vertical shaft 24 which is rotatably supported in a suitable bracket 25. In order that the gates may move in unison each shaft 24 carries at its upper end a horizontal

arm 27. One of these arms extends in a generally forward direction and the other extends in a generally rearward direction, and they are connected by a horizontal rod 28 sufficiently high above the conveyor to allow the stock to pass beneath. The gates are preferably biased toward their closed position, and for this purpose each shaft 24 has an arm 29 secured thereto, each arm being connected by a link 31 to a bell crank lever 32 having a weight 33 thereon. The two bell crank levers are pivotally supported on opposite sides of the conveyor 16.

With the construction as so far described, the front end of the stock will issue from the vibrator 12, ordinarily at very high speed, and before the stock has time to tip laterally it will strike the closed gates 23. Because of the converging arrangement of these gates, they will provide lateral support for the front end of the stock and at the same time they will retard the forward movement of the front end for a brief moment until the action of the vibrator has formed a few loops in the stock. The conveyor 16 of course tends to carry the stock forwardly at a low speed, and if the pressure against the gates increases sufficiently, they will open despite their bias and allow the stock to pass between them.

I preferably provide means to open and close the gates automatically in response to the arrival and departure of each piece of stock, the opening movement of course being delayed sufficiently to ensure the proper looping of the stock. For this purpose a suitable fluid motor 35 is mounted at one side of the conveyor 16, this motor having a reciprocable piston rod 36 which carries a pin 37. This pin is located in a slot 39 (Fig. 1) in a link 40 connected to one of the arms 29. This construction provides a lost motion connection between the motor and the gates, whereby the motor can effect a positive opening of the gates, but the gates can be closed only by the action of the weights 33 under the control of the motor. Some distance in front of the gates I provide a light source 42 (Fig. 1) arranged to project a light beam 43 across the path of the stock and toward a light sensitive device 44 which is preferably a photo-electric tube. Slightly in the rear of the gates I provide a second light source 46 arranged to project a light beam 47 across the path of the stock and toward a light sensitive device 48 which is preferably a photo-electric tube. Referring now to Fig. 4, it will be seen that the motor 35 is connected by pipes 49 and 50 to a four-way valve mechanism 51 having a slideable valve member 53 which is biased in one direction by a tension spring 54 and arranged to be moved in the opposite direction by a solenoid 55. A suitable pressure fluid, such as compressed air, is supplied to the valve mechanism 51 through a pipe 56. The various parts are so arranged that with the solenoid 55 de-energized and the valve member 53 held by the spring 54 in the position illustrated, air will flow through the pipe 50 to the motor 35, the pipe 49 being opened to atmosphere, and the motor will allow the gates 23 to be held closed by the weights 33. If now the solenoid 55 is energized, the valve member 53 will be moved to the opposite end of its stroke, reversing the connections to the motor 35, and the motor will immediately open the gates.

The energization of the solenoid 55 is controlled by the action of the stock as it interrupts the light beams which are directed toward the photo-electric tubes 44 and 48. For this purpose there

is provided a source 58 of electricity under the control of a main switch 59, and the flow of current from this source 58 through the solenoid 55 is controlled by two switches 60 and 61, which are connected in parallel. The switch 60 is of the normally closed type controlled by an amplifier and relay 63 of well-known construction which is connected in circuit with the photo-electric tube 48 and a source of electricity shown as a battery 64, these parts being so arranged that when light strikes the tube 48 current will flow through the relay 63, and the switch 60 will be opened. The switch 61 is also of the normally closed type and is controlled by a solenoid 66 which is connected in series with a normally open switch 67 controlled by an amplifier and relay 68 of well-known construction. The relay 68 is connected in circuit with the photo-electric tube 44 and a source of electricity shown as a battery 69, these parts being so arranged that when light strikes the tube 44 current will flow through the relay 68, closing the switch 67, energizing the solenoid 66, and opening the switch 61. Means is preferably provided to delay slightly the closing movement of the switch 61 when the solenoid 66 is de-energized, and for this purpose the plunger of this solenoid is connected to the piston 71 of an oil dashpot 72, this dashpot having two by-pass conduits 73 and 74, both of which connect to opposite sides of the piston. The conduit 73 is provided with a valve 76, which is preferably of the needle type, and the conduit 74 is provided with a check valve 77 which opens in a direction to allow the switch 61 to open freely when the solenoid 66 is energized. When the solenoid 66 is de-energized the closing movement of the switch 61 is delayed, since the oil in the dashpot is forced to flow through the valve 76, which can be adjusted to produce the desired delay period.

The operation of the invention will now be apparent from the above disclosure. With the main switch 59 closed, the lamps 42 and 46 lighted, and no stock in position to interrupt the light beams 43 and 47, the switch 60 will be held open by the relay 63, the switch 67 will be held closed by the relay 68, the solenoid 66 will be energized, the switch 61 will be held open thereby, and the solenoid 55 will be de-energized. The spring 54 will hold the valve 53 in the position shown, and the gates 23 will be closed. When the front end of the stock reaches the light beam 43 and interrupts the same, light will no longer fall on the tube 44, and the switch 67 will therefore open, de-energizing the solenoid 66. The switch 61 will start to close, but its movement will be delayed by the action of the dashpot 72, since the oil therein must flow through the needle valve 76 as the piston 71 descends. In the meantime, the front end of the stock, which may be traveling at very high speed, has reached the closed converging gates 23. These gates will support the front end of the stock laterally and impede its forward progress for a brief moment until a few loops have been formed in the stock by the action of the vibrator 12, somewhat as shown in Fig. 1, it being understood that the exact shape which the stock will assume will depend upon several factors, including the particular angular position of the vibrator when the front end issues therefrom. When sufficient loops have been formed in the stock to render it self-supporting and prevent it from falling over laterally, the switch 61 will have completed its closing movement under the influence of the

dashpot 72. This will energize the solenoid 55, which will move the valve member 53 in opposition to the spring 54 and admit air through the pipe 49 to the motor 35, and the motor will open the gates 23 and allow the looped stock to be carried slowly along by the conveyor 16. If for any reason the pressure of the stock against the gates 23 becomes excessive before they are opened by the automatic control, this pressure will itself open the gates in opposition to the comparatively light weights 33, the lost-motion slot 40 allowing this opening movement to take place without moving the piston rod 36. As soon as the front end of the stock passes through the gates and interrupts the light beam 47, the switch 60 will close, but this will have no immediate effect, since the solenoid 55 is already energized. The pinch rolls 10 will continue to deliver the stock at high speed and the vibrator 12 will continue to form loops therein throughout the entire length of the piece. When the rear end of the stock has passed the light beam 43, light will again fall on the tube 44, closing switch 67, energizing solenoid 66 and opening switch 61 without delay, since the check valve 77 will allow rapid upward movement of the piston 71. Solenoid 55 will remain energized through the closed switch 60. When the rear end of the stock has passed the light beam 47, light will again fall on the tube 48, and the switch 60 will be opened, de-energizing the solenoid 55. The spring 54 will return the valve member 53 to the position shown in Fig. 4, admitting air through the pipe 50 to the motor 35, and the motor will immediately close the gates 23 in readiness for the next piece of stock.

It will now be clear that the invention makes it possible to deliver comparatively wide thin strip metal in an upright position and form loops therein without danger of the front end of the stock tipping over laterally and causing subsequent handling difficulties. This is brought about by comparatively simple, inexpensive and dependable apparatus which operates entirely automatically to provide the necessary lateral support for the stock and to withdraw this support at the proper time.

Having thus described my invention, what I claim as new and desire to secure by Letters Patent is:

1. Apparatus for handling strip metal comprising a substantially horizontal conveyor, means to deliver strip metal stock in an upright position to the conveyor, a guide for the stock movable back and forth laterally to form a series of loops in the stock, a barrier mounted in the path of the stock arranged to prevent the continued forward movement of the front end thereof, means to move the barrier out of the path of the stock shortly after the front end of the stock has reached the same, and means to return the barrier to its original position after the rear end of the stock has passed the same.

2. Apparatus for handling strip metal comprising a substantially horizontal conveyor, means to deliver strip metal stock in an upright position to the conveyor, a guide for the stock movable back and forth laterally to form a series of loops in the stock, a pair of gates mounted in the path of the stock and forming a barrier which converges in the direction of stock travel to provide lateral support for the front end of the stock until one or more initial loops have been formed in the stock, and means providing

pivotal supports for the outer edges of the gates so that they may swing open to allow the looped stock to pass between them.

3. Apparatus for handling strip metal comprising a substantially horizontal conveyor, means to deliver strip metal stock in an upright position to the conveyor, a guide for the stock movable back and forth laterally to form a series of loops in the stock, a pair of gates mounted in the path of the stock and forming a barrier which converges in the direction of stock travel to provide lateral support for the front end of the stock until one or more initial loops have been formed in the stock, means providing pivotal supports for the outer edges of the gates so that they may swing open to allow the looped stock to pass between them, and a motor connected to the gates to actuate the same.

4. Apparatus for handling strip metal comprising a substantially horizontal conveyor, means to deliver strip metal stock in an upright position to the conveyor, a guide for the stock movable back and forth laterally to form a series of loops in the stock, a pair of gates mounted in the path of the stock and forming a barrier which converges in the direction of stock travel to provide lateral support for the front end of the stock until one or more initial loops have been formed in the stock, means providing pivotal supports for the outer edges of the gates so that they may swing open to allow the looped stock to pass between them, and a motor connected to the gates to actuate the same.

5. Apparatus for handling strip metal comprising a substantially horizontal conveyor, means to deliver strip metal stock in an upright position to the conveyor, a guide for the stock movable back and forth laterally to form a series of loops in the stock, a pair of gates mounted in the path of the stock and forming a barrier which converges in the direction of stock travel to provide lateral support for the front end of the stock until one or more initial loops have been formed in the stock, means providing pivotal supports for the outer edges of the gates so that they may swing open to allow the looped stock to pass between them, means biasing the gates toward their closed position, a motor, and means providing a lost motion connection between the motor and the gates.

6. Apparatus for handling strip metal comprising a substantially horizontal conveyor, means to deliver strip metal stock in an upright position to the conveyor, a guide for the stock movable back and forth laterally to form a series of loops in the stock, a pair of gates mounted in the path of the stock and forming a barrier which converges in the direction of stock travel to provide lateral support for the front end of the stock until one or more initial loops have been formed in the stock, means providing pivotal supports for the outer edges of the gates so that they may swing open to allow the looped stock to pass between them, means projecting a light beam across the path of the stock in front of the gates, means to open the gates in response to interruption of said light beam by the front end of the stock, means projecting a second light beam across the path of the stock in the rear of the gates, and means to close the gates in response to the second light beam after the rear end of the stock has passed the same.

6. Apparatus for handling strip metal comprising a substantially horizontal conveyor, means to deliver strip metal stock in an upright position to the conveyor, a guide for the stock movable back and forth laterally to form a series of loops in the stock, a pair of gates mounted in the path of the stock and forming a barrier which converges in the direction of stock travel to provide lateral support for the front end of the stock until one or more initial loops have been formed in the stock, means providing pivotal supports for the outer edges of the gates so that they may swing open to allow the looped stock to pass between them, means projecting a light beam across the path of the stock in front of the gates, means projecting a second light beam across the path of the stock in the rear of the gates, a fluid-pressure motor connected to the gates to actuate

the same, a solenoid valve to control the flow of pressure fluid to the motor, and means to so control the solenoid valve in response to the interruptions of said light beams by the stock as to open the gates shortly after the front end of the stock has reached the same and to close the gates shortly after the rear end of the stock has passed the same.

7. Apparatus for handling strip metal comprising a substantially horizontal conveyor, means to deliver strip metal stock in an upright position to the conveyor, a guide for the stock movable back and forth laterally to form a series of loops in the stock, a barrier mounted adjacent the conveyor, means supporting the barrier for movement into and out of the path of the stock, and means yieldably urging the barrier toward a position in the path of the stock and so constructed that the barrier will move out of the said path in the event the pressure of the stock thereagainst becomes excessive.

8. Apparatus for handling strip metal comprising a substantially horizontal conveyor, means to deliver strip metal stock in an upright position to the conveyor, a guide for the stock movable back and forth laterally to form a series of loops in the stock, a barrier mounted adjacent the conveyor, and means supporting said barrier for movement between an open and a closed position, the barrier when open being out of the path of the stock, and when closed providing surfaces located in the path of the stock and converging in the direction of travel thereof to provide lateral support for the front end of the stock.

9. Apparatus for handling strip metal comprising a substantially horizontal conveyor, means to deliver strip metal stock in an upright position to the conveyor, a guide for the stock movable back and forth laterally to form a series of loops in the stock, a barrier mounted in the path of the stock arranged to prevent the continued forward movement of the front end thereof, and means to move the barrier out of the path of the stock shortly after the front end of the stock has reached the same.

10. Apparatus for handling strip metal comprising a substantially horizontal conveyor, means to deliver strip metal stock in an upright position to the conveyor, a guide for the stock movable back and forth laterally to form a series of loops in the stock, a barrier mounted adjacent the conveyor, and means supporting the barrier for movement between an open and a closed position, the barrier when open being out of the path of the stock, and when closed being located in the path of the stock to prevent the continued forward movement of the front end thereof.

11. Apparatus for handling strip metal com-

prising a substantially horizontal conveyor, means to deliver strip metal stock in an upright position to the conveyor, a guide for the stock movable back and forth laterally to form a series of loops in the stock, a barrier mounted adjacent the conveyor, and means supporting the barrier for movement between an open position out of the path of the stock and a closed position in the path of the stock, the barrier being yieldably biased toward its closed position and so arranged that it will move toward its open position in the event the pressure of the stock thereagainst becomes excessive.

12. Apparatus for handling strip metal comprising a substantially horizontal conveyor, means to deliver strip metal stock in an upright position to the conveyor, a guide for the stock movable back and forth laterally to form a series of loops in the stock, a barrier mounted adjacent the conveyor, and means pivotally supporting the barrier for a swinging movement between an open and a closed position, the barrier when open being out of the path of the stock, and when closed being located in the path of the stock to prevent the continued forward movement of the front end thereof.

13. Apparatus for handling strip metal comprising a substantially horizontal conveyor, means to deliver strip metal stock in an upright position to the conveyor, a guide for the stock movable back and forth laterally to form a series of loops in the stock, a barrier mounted adjacent the conveyor, means supporting the barrier for movement between an open and a closed position, the barrier when open being out of the path of the stock, and when closed being located in the path of the stock to prevent the continued forward movement of the front end thereof, and a motor connected to the barrier to actuate the same.

14. Apparatus for handling strip metal comprising a substantially horizontal conveyor, means to deliver strip metal stock in an upright position to the conveyor, a guide for the stock movable back and forth laterally to form a series of loops in the stock, a barrier mounted adjacent to the conveyor, means supporting the barrier for movement between an open and a closed position, the barrier when open being out of the path of the stock, and when closed being located in the path of the stock to prevent the continued forward movement of the front end thereof, means biasing the barrier toward its closed position, a motor, and means providing a lost motion connection between the motor and the barrier, the barrier being arranged to yield in the event the pressure of the stock thereagainst becomes excessive.

MYLES MORGAN.
